[57] **CLAIM**

The ornamental design for a handheld printer for printing on small objects, as shown and described.

DESCRIPTION

FIG. 1 is a reduced perspective view showing our new design;

FIG. 2 is a front plan view thereof;

FIG. 3 is a right side elevational view thereof, the left side being a mirror image of the right side;

FIG. 4 is a bottom end view thereof;

FIG. 5 is a top end view thereof; and,

FIG. 6 is a back plan view thereof.

FIG. 1.

FIG. 3.

FIG. 2.

FIG. 4.

FIG. 6.

FIG. 5.
